UNITED STATES PATENT OFFICE.

ANTHONY E. WEINGARTNER, OF BETHLEHEM, PENNSYLVANIA, ASSIGNOR TO AMERICAN ENGINEERING COMPANY, OF PHILADELPHIA, PENNSYLVANIA, A CORPORATION OF PENNSYLVANIA.

ROTARY PUMP OR MOTOR.

Application filed May 13, 1921. Serial No. 469,152.

This invention relates to machines of the type wherein a series of pistons mounted in a rotary cylinder barrel in cylinders which parallel the axis of the shaft upon which the said cylinder barrel is mounted, act in conjunction with a fixed cam ring either to produce rotation of the said rotor, when an actuating fluid is applied to operate the said pistons, or, when power is applied to the shaft to rotate the rotor, to give a reciprocating motion to the said pistons to cause the machine to operate as a pump.

A clearer understanding of the invention will be more readily obtained from the attached drawings, in which:

Figure 1, is a vertical section of my machine;

Fig. 2, is a partial horizontal section showing the upper portion of the casing removed;

Fig. 3, is a horizontal section of the machine on line 3-3 of Fig. 14 with the rotor and shaft removed;

Fig. 4, is a partial vertical section of the rotor and allied moving elements;

Fig. 5, is an end elevation of the rotor and shaft;

Figs. 6 and 7, are respectively outside and inside elevations of one of the port heads or end covers;

Fig. 8, is a section taken on the line 8-8, Fig. 7;

Figs. 9 and 10, are respectively side and inside elevations of the other of said port heads or end covers;

Figs. 11, 12 and 13, are respectively sections taken on the lines 11-11, 12-12 and 13-13, Figs. 9 and 10, respectively;

Fig. 14, is an end elevation of the machine;

Fig. 15, is a vertical section of the machine on the line 15-15, Fig. 1;

Fig. 16, is a vertical section of the casing on the line 16-16, Fig. 1, and

Fig. 17, is a development of the rotor cylinder and of the casing illustrating the disposition of admission and exhaust ports.

With reference to the drawings, the machine consists of a substantially cylindrical casing 1, the open ends of which are adapted to be closed by end covers or port heads 2 and 3 respectively, said heads being attached to the casing 1 by means, in the present instance, of bolts 4 which pass through suitable apertures near the periphery of the

said end covers and are threaded into said casing.

Journalized in suitable journals 5 and 6 in the port heads 2 and 3 respectively is a main shaft 7, said shaft extending in the present instance completely through the said port head 2 and projecting beyond the outer face thereof. Keyed to the shaft 7 intermediate the said port heads is a cylindrical rotor 8, which rotor is most clearly shown in Figs. 4 and 5, having at one side thereof a peripheral extension 9, in which is formed a series of cylindrical openings 10, said openings 10 being evenly spaced around the entire circumference of the said extension, as most clearly shown in Fig. 5.

Mounted upon the periphery of the rotor 8 and splined thereto by means of a key 11 is a ring-shaped element 12 corresponding in form and dimensions with the peripheral extension 9, said ring 12 having formed therein a series of cylindrical passages 13 which correspond in size and number with the said openings 10, 10, in the peripheral extension 9, the said ring 12 being so disposed upon the rotor 8 that the said openings 10 and 13 are in alignment, the common axes of the oppositely disposed pairs of openings being parallel to the axis of the rotor and of the shaft 7.

The outer side surfaces of the peripheral extension 9 and of the ring 12 are adapted to bear respectively against the inner surfaces of the port heads 2 and 3, and a sealing contact is maintained in the said abutting surfaces of the rotor element and the port heads by means of collar nuts 14, 14, threaded upon the rotor 8, and as most clearly shown in Figs. 1 and 4, said nuts being adapted to bear against the inner face of the ring 12 to force the said ring against the inner surface of the port head 3, and similarly to force the outer surface of the peripheral extension 9 of the rotor against the inner face of the port head 2.

Extending inwardly from the interior of the casing 1 is an annular lug 15, said lug being substantially centrally disposed between the inner faces of the port heads 2 and 3. A port 16 is formed in the top of the casing 1, and the said lug 15 extends around the casing from the edges of the said port 16, as most clearly shown in Fig. 16. To the

said lug 15 is adapted to be secured by means of bolts 17, a cam ring 18, the said cam ring being of wave-like formation, as most clearly illustrated in Figs. 3 and 17. The cam ring

18 is in the form of a complete ring, and a section 19 thereof underlying the said opening 16 is detachable from the main section and may be removed therefrom.

Established within the cylindrical openings 10 and 13, are pistons 20, said pistons having suitably secured thereto rollers 21 which are adapted to engage the opposite side faces of the cam 18, in the manner clearly illustrated in Figs. 1 and 2. In the present instance, the pistons 20 which occupy the respective sets of aligned cylinders 10—13 are united by an arm 22, and the said rollers 21 are mounted upon spindles 23 which extend between this arm and an inward projection 24 on each of the said pistons.

It will be clear from the foregoing description that as the rotor 8 revolves the said respective sets of pistons 20, 20, will reciprocate laterally in a direction parallelling the axis of the shaft 7, in accordance with the formation of the cam 18, the roller 21 of one of said united pairs of pistons occupying a recess in said cam when the opposite roller 30 rests against an opposite extension.

As previously stated, the machine is adapted to be employed either as a motor or as a pump, and suitable ports are provided in the said port heads 2 and 3 for the admission and exhaust to and from the outer end of the cylindrical openings 10 and 13 of an actuating fluid.

As most clearly shown in Fig. 2, the port heads 2 and 3 are each provided with a pair 40 of annular grooves in the peripheries thereof, the said grooves of the port head 2 being indicated by the reference numerals 26 and 27, and the grooves of the port head 3 being indicated by the reference numerals 28 and 29, and these grooves are adapted to communicate by means of suitable ports with chambers or manifolds 30, 31, 32 and 33, formed in the said casing 1.

Ports 34 and 35 axially disposed in the port head 2 form respectively communication between the grooves 26 and 27 and the outer ends of the cylindrical openings 10, while similar axially disposed ports 36 and 37 establish communication respectively between the grooves 28 and 29 and the outer ends of the cylindrical openings 13. The said ports 34, 35, 36 and 37, are so disposed in their respective port heads that the ports 34 in the port head 2 lie directly opposite to the ports 36 of the port head 3, while the ports 35 of the port head 2 lie directly opposite the ports 37 of the port head 3, the said ports 34 and 35, as most clearly shown in Fig. 7, being arranged alternately in a circle, the center of which is the center line

of the shaft 7, the ports 36 and 37 being similarly alternately mounted in the port head 3.

It will be seen from the above that when one of the cylindrical openings 10 registers 70 with one of the ports 34, the said cylindrical opening 18 will register with one of the ports 36 of the port head 3, while when the said cylindrical opening 10 registers with one of the ports 35, the opposite cylindrical 75 opening 13 will register with one of the ports 37. In the present instance, the manifolds 30 and 32 are, we will suppose, intake manifolds, while the manifolds 31 and 33 are exhaust manifolds, and the arrangement 80 is such that while the grooves 27 and 29 communicate through ports 40, 40, with the manifolds 30 and 32, the grooves 26 and 28 communicate by means of ports 41, 41, with the manifolds 31 and 33. 85

It will thus be seen that when one end of the tandem cylinder formed by each pair of oppositely disposed cylinder openings 10 and 13 is in communication with the exhaust, the opposite end will be in communication 90 with the intake manifolds.

Extending inwardly in the present instance from the outer face of the port head 3 are ports 42 and 43 constituting respectively exhaust and intake ports for an actuating 95 fluid. The said port 43 communicates with a centrally disposed annular chamber 44, from which extend passages 45, 45, into the bottom of the said groove 29 whereby an actuating fluid entering through the port 43 100 is distributed through the said groove 29 to ports 37 of the port head 3, and to the intake manifolds 30 and 32, from whence it passes through the ports 40 to the groove 27 of the port head 2, said actuating fluid 105 then passing through the ports 34 into the cylinder openings 10.

From the port 42 I extend passages 46, 46, into the base of the groove 28, whereby a passage is afforded for the actuating fluid 110 which is exhausted from the cylinder openings 13 through the ports 36, and also for the actuating fluid which is exhausted from the cylinder openings 10 through the ports 35 into the grooves 26, these latter grooves 115 communicating with the said manifolds 31 and 33, as previously stated, through the port 41 and also with the groove 28.

The operation of the device is as follows: An actuating fluid, introduced in the present 120 instance through the port 43, is led in the manner previously explained to the ports 34 and 37, at the same time the ports 35 and 36 being opened to the exhaust also, as previously described. Since the ports 34 and 125 36 are oppositely disposed, as also are the ports 35 and 37, it will be apparent that as the rotor 8 revolves, the opposite ends of the tandem cylinders formed by each pair 130 of oppositely disposed cylindrical openings 130

- 10 and 13 will be brought respectively into communication with an intake and an exhaust port, and that furthermore first one end of said tandem cylinders and then the other will communicate with an intake port. The admitted actuating fluid acting alternately upon the pistons 20 in the respective cylinder openings 10 and 13, will drive them inwardly so that the rollers 23 are forced 10 against the side edges of the wave cam 18, his pressure of the rollers upon the inclined edges of the cam creating a substantially tangential thrust at the periphery of the said rotor, causing the latter to revolve.
- 15 When the engine is employed in this manner and the pistons are actuated by the actuating fluid, the machine is employed as a motor, but when on the other hand power is applied to the shaft 7 to cause the rotor to 20 revolve, it will be apparent that as the rotor revolves, the cam will cause the pistons to reciprocate in their respective cylinders whereby the machine acts as a pump, drawing a liquid through one of the ports, 25 42 or 43, and ejecting it through the other.

It will be noted that provision is made for removal of the pistons 20 without necessitating removal of the port heads 2 and 3. This feature is enabled by the addition of 30 the handhole 16 previously described and the removable cam section which underlies the said opening. By removal of an insert plug 47 which extends through the said port head 3, and of the said removable cam section, it is apparent that any or all of the 35 pistons may be removed and replaced through the said plug hole without removal of the port heads. This also provides for adjustment of the collar nuts 14 to take up 40 any wear upon the faces of the rotor elements.

It is clear that the above described engine will operate with a single faced wave cam and with one cylinder barrel, or as a half 45 unit of the machine herein described, and that considerable other modification is possible with no departure from the essential features of the invention.

I claim:

- 50 1. In a machine, the combination, of a rotor having a peripheral extension at one side, a ring removably mounted upon the periphery of said rotor, said ring being similar to said peripheral extension and 55 being spaced apart therefrom, oppositely disposed series of cylinders in the said extension and in the ring, a fixed cam ring adapted to occupy the space between the said extension and ring, and pistons in said 60 cylinders adapted continuously to bear against the opposite sides of the said cam ring.
2. In a machine, the combination of a 65 casing, end plates for said casing, a rotor mounted in said casing and having a per-
- ipheral extension at one side, a ring substantially similar in form to said peripheral extension mounted upon the periphery of said rotor, means for preventing relative rotational movement between the ring and 70 the rotor while permitting said ring to move axially of said rotor, and means for causing the outer faces of the said peripheral extension and of the said ring to bear against 75 the inner surfaces of the respective end plates.
3. In a machine, the combination with a casing having ported end plates, of a shaft journaled in the end plates, a rotor splined to the shaft and confined by the end plates, 80 said rotor having cylindrical openings adapted to register with the ports in the end plates, pistons in said openings, and means for expanding the rotor to insure close contact between the sides thereof and 85 the inner faces of the end plates.
4. In a machine, the combination of a casing, end plates for said casing, a rotor mounted in said casing and having a peripheral extension at one side, a ring substantially similar in form to said peripheral extension mounted upon the periphery of 90 said rotor, means for preventing relative rotational movement between the ring and the rotor while permitting said ring to move axially of said rotor, means for causing the outer faces of said peripheral extension and of the said ring to bear against the inner 95 surfaces of the respective end plates, and means for actuating said rotor comprising 100 cylinders in the rotor, pistons in said cylinders, and a relatively fixed cam intermediate the said peripheral extension and said ring and operatively connected with the pistons.
5. In a machine, the combination of a 105 casing, end plates for said casing, a rotor mounted within the casing and having at one side thereof an annular peripheral extension, a ring mounted upon the periphery of said rotor and spaced apart from said extension, means for preventing relative rotational movement between the rotor and the ring, and lock nuts carried by said rotor intermediate the ring and the said extension 110 for retaining said ring in a position upon the rotor body affording close contact between the outer surfaces of the extension and of the ring and the inner surfaces of the respective end plates.
6. In a machine, the combination of a casing, end plates for said casing, a rotor mounted within the casing and having at one side thereof an annular peripheral extension, a ring mounted upon the periphery of said rotor and spaced apart from said extension, means for preventing relative rotational movement between the rotor and the ring, lock nuts carried by said rotor intermediate the ring and the said extension for 115 retaining said ring in a position upon the 120 rotor body.
7. In a machine, the combination of a casing, end plates for said casing, a rotor mounted within the casing and having at one side thereof an annular peripheral extension, a ring mounted upon the periphery of said rotor and spaced apart from said extension, means for preventing relative rotational movement between the rotor and the ring, lock nuts carried by said rotor intermediate the ring and the said extension for 125 retaining said ring in a position upon the 130 rotor body.

- rotor body affording close contact between the outer surfaces of the extension and of the ring and the inner surfaces of the respective end plates, and means for actuating 5 said rotor comprising cylinders in the rotor, pistons in said cylinders, and a relatively fixed cam intermediate the said peripheral extension and said ring and operatively connected with the pistons.
- 10 7. In a machine, the combination of a frame, end plates for said frame, a rotor mounted in said frame, axially disposed cylindrical openings in said rotor, pistons mounted in said openings, one of said end plates having an opening therein adapted to register with the openings of the said rotor as the latter rotates, and a removable plug normally closing the opening in said end plate.
- 15 8. In a machine, the combination of a frame, end plates for said frame, a rotor mounted in said frame axially disposed cylindrical openings in said rotor, pistons mounted in said openings, one of said end plates having an opening therein adapted to register with the openings of said rotor as the latter rotates, a removable plug normally closing the opening in said end plate, a cam ring to which said pistons are operatively connected, and a detachable section in said cam ring opposite the said end plate opening.
- 20 9. In a machine, the combination of a frame, a rotor mounted in the frame and having axially disposed cylindrical openings, pistons in said openings, end plates for the frame having intake and discharge ports directly communicating with said openings, and one of said end plates having a plug mounted opposite one of said ports and removable from the outside of the plate to provide access through the port to the cylinder openings.
- 25 10. In a machine, the combination of a frame, a rotor mounted in the frame and having axially disposed cylindrical openings, pistons in said openings, a cam to which said pistons are operatively connected, said cam having a detachable section, end plates for the frame having intake and discharge ports directly communicating with said ro-
- tor openings, and one of said end plates having a plug mounted opposite one of said ports and the detachable section of the cam and removable from the outside of the plate to provide access through the port to the cylinder openings.
- 30 11. In a machine, the combination of a casing, a rotor in said casing, said rotor having a series of cylindrical openings therein disposed on the arc of a circle concentric with said rotor, a fixed cam ring mounted opposite one end of said openings, a section of said cam ring being removable, and said casing having an opening therein opposite 65 said removable cam section.
- 35 12. In a machine, the combination of a casing, a rotor in said casing, said rotor having a series of cylindrical openings therein disposed on the arc of a circle concentric 70 with said rotor, a fixed cam ring mounted opposite one end of said openings, a section of said cam ring being removable, and pistons in said cylindrical openings each having an integral member embracing the 75 opposite edges of the cam ring and detachable from the ring only by removal of said removable section.
- 40 13. In a machine, the combination with a frame, of a rotor mounted in the frame and having two separated and aligned series of cylinder openings, pistons in said cylinders, means rigidly connecting the pairs of aligned pistons, a cam ring intermediate the aligned cylinders operatively associated with 80 the pistons, and means for detaching a section of the cam ring to permit withdrawal of the connected pistons from the cylinders.
- 45 14. In a machine, the combination of a casing, a rotor in said casing, end plates for 90 said casing, cylindrical openings extending inwardly from the side faces of said rotor, said cylindrical openings being disposed upon the arc of a circle concentric with said rotor, positive means on the rotor for expanding the rotor to insure close contact between the sides thereof and the inner faces of the end plates, ports in the said end plates adapted to register with the ends of said cylindrical openings, and pistons adapted 100 to operate in said cylindrical openings.

ANTHONY E. WEINGARTNER.
